UNITED STATES PATENT OFFICE.

GEORGE F. MCGILL, OF MARENGO, ILLINOIS, ASSIGNOR TO MCGILL METAL PRODUCTS COMPANY, OF CHICAGO, ILLINOIS, A CORPORATION OF ILLINOIS.

HAND PUNCH.

Application filed March 21, 1925. Serial No. 17,198.

The invention relates to punches, and particularly to hand punches, such as are usually employed by conductors, waiters, and others for punching tickets, cards, sheets, 5 and the like.

A punch having some of the features and characteristics of the punch referred to in this application is shown and described in United States Letters Patent to Albert Beck, 10 Patent Number 1,417,488, issued May 30, 1922, and also in the application of Albert Beck for United States Letters Patent, Serial Number 648,891, filed July 2, 1923.

It is one of the prime objects of the invention to provide a punch of the character above referred to with means whereby the male and female punching elements may be readily changed, substituted or replaced, and thus permit punch elements having different characters to be associated with the same punch frame and punch actuating mechanism.

It is another feature of the invention to employ a guide for the male punching element, which guide is provided with means for engaging the male punching element and holding it against rotation, or in other words, preventing it from moving out of register with the female die element, the 25 outline of which, and the outline of the male die element, in many instances, necessitating the accurate alignment with each other of both die elements to insure their proper operation.

It is another object of the invention to construct the guide, or bearing, for the die pin so that the ticket, card, or sheet to be punched may readily be viewed and the point of application of the die pin easily 35 and readily ascertained, thereby permitting the dies to be accurately applied to the desired place on the ticket, card, or sheet.

A further object of the invention is to construct the guide, or bearing, for the die pin so that it will permit the association with, and operation of, a lever with said die pin while the pin is in operative position within the guide.

It is a further object of the invention to 45 provide an arrangement of lever and die pin, or more particularly the connection of the lever and the die pin, whereby the pin

may be effectively operated in the guide or bearing and always be at right angles to the female die element, and without any rotative 55 movement of the die pin.

An additional object of the invention is to, preferably, form the body, grip, and lever portions of the punch from sheet metal stampings, which are formed into proper 60 shapes and suitably finished and assembled.

One of the objects of the invention is to construct the jaw of the punch adjacent the die pin in such a manner as to strengthen, support, and maintain the guide or bearing 65 in its proper place in the jaw, and, at the same time, close the end of the jaw between the sides thereof and the bearing to keep extraneous matter from interfering with the operating parts of the punch and also to improve the appearance of the punch.

In addition to the above enumerated objects, it is a further object to form one of the jaws of the punch frame so as to provide a seat for one of the dies of the punch, 70 and to receive an element which cooperates with said die to hold the latter relatively to the jaw.

It is another feature of the invention to provide a holding element for one of the die 80 elements which is removable from the punch frame, so as to permit the ready substitution of one die element for another, and to further construct said holding element so that it will receive the die element.

In addition it is an object to construct both the die element and the holding means so that one will cooperate with the other and prevent the relative rotation of one with respect to the other.

A further object of the invention is to provide a punch of the character described with a chamber, into which the punchings from the tickets, cards, sheets, and the like, may fall and be held; to provide this chamber with an opening, whereby the punchings may be removed from the chamber, and to provide a closure for the chamber, which closure is held in slidably relation to the punch by means of lips on the closure extending into grooves provided in the body 95 portion of the punch.

It is a further object of the invention to provide a stop for limiting the movement of

the closure with relation to the opening in the chamber and to form this stop in the closure.

The invention will be explained and more readily understood when read in conjunction with the accompanying drawings, in which various modifications, of which the invention is susceptible, are illustrated, it being, however, obvious that changes and modifications may be made without departing from the spirit of the appended claims forming a part hereof.

In the drawings:

Figure 1 is a side elevation of a punch constructed according to one embodiment of the invention.

Figure 2 is a central, longitudinal section of the punch illustrated in Figure 1.

Figure 3 is a section taken on line 3—3 of Figure 2.

Figure 4 is a plan view of a portion of the punch illustrated in Figures 1, 2, and 3.

Figure 5 is a plan view of a blank or stamping which, when formed, produces a body portion and a grip portion of the punch illustrated in Figures 1 and 2.

Figure 6 is an enlarged, perspective view of the guide element, or bearing, employed for guiding the movable punching die pin illustrated in Figures 2, 3, 4 and 7.

Figure 7 is a perspective view of the punching die pin.

Figure 8 is a plan view of the female die holding element showing a cutting die associated therewith.

Figures 9 to 12, both inclusive, illustrate female dies having various characters, which dies may be substituted for each other and associated with the punch frame.

Figure 13 is a sectional view, partially in elevation, of a portion of the punch frame showing another arrangement which may be employed to form a connection between the actuating lever and the male punching element.

Figure 14 is a section taken on line 14—14 of Figure 13.

Figure 15 is a view similar to Figure 13 illustrating another structure which may be employed for associating the actuating lever and the male punching element.

Figure 16 is a section taken on line 16—16 of Figure 15.

Figure 17 is a view of a punching element and lever for actuating the punching element, and illustrates another manner in which a connection between a die element and the lever mechanism may be found, and,

Figure 18 is a section taken on line 18—18 of Figure 17.

In the punch of the invention there is employed a body portion 16 having a grip portion 17 extending therefrom, the body portion 16 being formed to provide the jaws 18 and 19, which are separated by a slot 20,

into which is inserted the ticket, card, or sheet to be punched. The jaws 18 and 19, respectively, carry the die cutting elements of the punch, i. e., the male punching die pin 21 and the female die element 22. The die actuating lever 23, having the grip portion 24, is pivotally secured to the body portion through the medium of the pin 25. The lever 23 is associated with the punching die pin 21 and is constructed so as to actuate the die pin 21 and cause it to be brought into cooperative relation with the female die element, 22, to punch the tickets, cards, and sheets. An expansion spring 26 is arranged between the grip portions 17 and 24 so that the grip portions will normally assume an extended relation. One end of the expansion spring is connected to the finger ring 27 and the other end rests against the inner portion of the grip 24.

The body portion 16, with its grip 17, is formed of a suitable blank, which is cut out or stamped in a manner to provide the structure illustrated in Figures 1 and 2 when bent into shape. The blank is clearly shown in Figure 5 of the drawings. When the blank is bent along the dotted lines *a*, *b*, it will provide the side portions of the jaws 18 and 19. The blank will then be bent inwardly along the dotted lines *c* and *d* and secured together in any suitable manner and thus form a wall 28 of a chamber 29, which is produced in the lower jaw 19 of the punch. This chamber is formed to hold the punchings from the tickets, cards, and sheets. The blank illustrated in Figure 5 is cut out, as indicated at 30 and 31, which provides the opening 32 when the blank is bent into the shape shown in Figures 1 and 2. The opening thus formed provides a means through which the punchings from the tickets, cards, and sheets may be dropped from the chamber 29. When the blank is formed in the shape illustrated in Figures 1 and 2, the cut out portions 33 and 34 will provide the slot 20.

The blank shown in Figure 5, is further provided with the aperture 35 and the V-shaped opening 36. The aperture 35 provides a means for receiving the guide or bearing 37 for the die pin 21. The aperture 35 communicates with the V-shaped opening 36 and provides a space which will permit the operator to view the indicia which are punched from the ticket, card, or sheet. The provision of the openings described, together with the opening in the guide or bearing 37, more particularly hereinafter described, assists in the accurate application of the male punching die 21 to the ticket, card, or sheet. A plate 38 is suitably arranged in the notches 39, 40, of the blank, and secured therein. The plate 38 is apertured to receive the guide or bearing 37.

The opening 32, formed by the cut out portions 30 and 31, is closed by a slidible

closure 41, which is bent to partially surround the lower jaw 19 of the punch, and is provided with the inwardly extending flanges or lips 42 and 43, as shown in Figure 3, which extend into and slide in the slots or grooves 44 and 45 in the opposite side walls of the chamber 29 of the jaw 19. The closure 41 is provided with an abutment 46 to limit the movement of the closure 41, which engages the opposite extremities of the opening 32 and limits the movement of the closure in both directions. The construction of the abutment 46 and the cut out 47 on each side of the closure 41 furnish means to move the closure with relation to the jaw 19. The top and end walls of the chamber 29 are formed by the plate 48 which is secured and held between the side walls of the chamber 29, and has an aperture or vent 49. The plate 48 is provided with an aperture 50, and the depressed portion 51, the latter being provided to receive certain other elements which enter into the structure at this point, which will be explained in detail hereinafter.

The guide, or bearing 37, as clearly shown in Figure 6, preferably, is tubular and is designed to be mounted in the aperture 35 in the jaw 18 and the aperture in the plate 38. It is held with relation to the jaw 18 by being brazed or welded thereto. The guide or bearing 37 is provided with an outer slot 52 which is arranged, when associated with the parts forming the punch, so that it coincides with the throat between the aperture 35 and the V-shaped opening 36. The bearing 37 is further provided with an inner, slotted aperture 53, through which one end of the die actuating lever 23 is passed into engagement with the slot 54 extending through the die pin 21. The edges of the slot 52 are formed to provide the inwardly projecting, parallel flanges 55 and 56, which are arranged in the longitudinally disposed guideways 57 and 58 of the die pin 21, which together provide a means for permitting the reciprocation of the die pin relatively to the guide and maintaining said pin against any rotative movement, thus preventing the die pin from assuming a position out of register with the female cutting element 22. The lower end 59 of the die pin corresponds to the configuration or outline of the opening in the female die element 22, and, as before stated, may be of any desired character, such as for instance, one of those illustrated in Figures 9 to 12. The guideways 57 and 58 are provided in that portion of the die pin 21 above the cutting or die part.

The female die element 22 and the means employed for holding it with relation to the jaw 19 of the punch includes the plate 60 which is located in the depression 51 of said jaw and held with relation thereto by means of the screws 61 and 62, which are passed

through apertures 63 and 64 respectively, provided in the wall 48 and the apertures 65 and 66 respectively provided in the plate 60. One edge of the plate abuts against the shoulders 39 and 40 shown in Figure 5, 70 which limit its movement in this direction. The plate 60 is further provided with a converging aperture 67 for the reception of the female cutting die 22, the sides of which correspond to the shape of the periphery of 75 the converging aperture 67 in the plate 60, which cooperate with each other and produce a means for securely yet removably holding the die element 22 against rotation with relation to other portions of the punch. 80

In Figures 13 and 14 there is shown a modified construction of the grip lever and the die pin, and also the means of connecting them to each other. The structure illustrated in these figures differs from that illustrated in Figures 1 and 2 in the connection between the lever 68 for actuating the die pin 69 and the said pin. In this structure the end of the actuating lever 68 is inserted into a slot 70 provided in the die pin 69. 90 The walls of the slot 70, with which the end of the actuating lever 68 engages, provide a contact between the faces of the walls and the end portion of the actuating lever 68, so that the lever when operated will actuate 95 the die pin 69.

In the modified arrangement illustrated in Figures 15 and 16 the actuating lever 71 is connected with the die pin 72 through the medium of the link 73, which is pivotally connected to the lever 71 at 74, and to the pin 72 at 75. In this structure a modified form of guide or bearing 76 for the die pin is illustrated, although a guide or bearing similar to the guide or bearing 37 may be employed, if desired. In the guide or bearing illustrated in Figures 15 and 16, the aperture, such as 54, is eliminated.

In the modified construction illustrated in Figures 17 and 18 the guide for the die pin 77 corresponds with the guide 37 illustrated in Figure 6, and, therefore, will not be further explained. This modified construction differs in the connection between the actuating lever and the die pin from that previously explained. In the structure of Figures 17 and 18 the die pin 77 is provided with an elongated aperture 78 and a pin 79, which is arranged transversely to the length of the die pin. The end of the lever 80 which cooperates with the die pin is provided with a bifurcated end 81, which is passed into the elongated aperture 78 into cooperative relation with the pin 79.

Having thus described my invention, 125 what I claim and desire to secure by Letters Patent is:

1. In a punch of the character described, the combination of a body member and an actuating member cooperatively connected 130

to the body member, said body member having portions which respectively, carry male and female punching elements, a unitary and separable guide member for the male punching element, said guide being mounted in said body member, said guide and male punching element having longitudinal inturned flanges and cut-out portions, respectively, which cooperate with each other to prevent rotation of the punching element relative to the guide.

2. In a punch of the character described, the combination of a body member and an actuating member cooperatively connected to the body member, said body member being provided with portions which, respectively, carry male and female punching elements, a unitary and separable guide for the male punching element, said male punching element having longitudinal notches on opposite sides thereof serving as guideways for the reception of means for preventing rotation of the punching element relatively to the guide.

3. In a punch of the character described, the combination of a body member and an actuating member cooperatively connected to the body member, said body member being provided with portions which, respectively, carry male and female punching elements, a tubular guide for the male punching element, said guide being provided with inwardly projecting longitudinally extending portions which engage the male punching element and prevent its rotation.

4. In a punch of the character described, the combination of a body member, and an actuating member cooperatively connected to the body member, said body member being provided with portions which, respectively, carry male and female punching elements, a tubular guide for the male punching element said guide being provided with inwardly projecting portions, and said punching element having grooves for the reception of said portions, said grooves being arranged lengthwise of the punching element and cooperating to prevent relative rotation of the punching element and guide.

5. In a punch of the character described, the combination of a body member and an actuating member cooperatively connected to the body member, said body member having portions which, respectively, carry male and female punching elements, said portion which carries the female punching element having a depression, a member in which the female punching element is arranged being carried in said depression above said portion which carries the female punching element.

6. In a punch of the character described, the combination of a body member and an actuating member cooperatively connected to the body member, said body member having upper and lower portions which, respective-

ly, carry male and female punching elements, and a guide member for the male punching element, said guide being mounted in said body member and being provided with means for preventing the relative rotation of the guide and male punching element, an apertured member removably secured to the lower body portion carrying the female punching element and above said lower body portion, said aperture in said member being provided to enable the female punching element to be removably mounted in said member.

7. In a punch of the character described, the combination of a body member and an actuating member cooperatively connected to the body member, said body member being provided with portions, which, respectively, carry male and female punching elements, a guide for the male punching element, said guide being provided with means whereby the actuating member may be associated with said male punching element, and said guide and male punching element being provided with means which cooperate with each other to hold the punching element against rotation, said portion of the body member which carries the female punching element being provided with an aperture and also with an apertured member whereby a female punching element may be interchangeably associated therewith, one aperture being disposed below the other.

8. In a punch of the character described, the combination of a body member and an actuating member cooperatively connected to the body member, said body member being provided with portions which, respectively, carry male and female punching elements, a guide for the male punching element, said guide being provided with means whereby the actuating member may be associated with said male punching element, said guide being provided with inwardly projecting longitudinally arranged projections which engage the male punching element and prevent its rotation, the portion of the body member which carries the female punching element having shoulders adapted to engage a member which is provided with the female cutting die and is adapted to be removably associated therewith.

9. In a punch of the character described, the combination of a body member, and an actuating member cooperatively connected to the body member, said body member being provided with portions which, respectively, carry male and female punching elements, a guide for the male punching element, said guide being provided with means whereby the actuating member may be associated with said male punching element, said guide and male punching element being provided with means which cooperate with each other to maintain the male punching element against

rotation, said portion of the body member which carries the female punching element being apertured, a removable element adapted to have a cutting element interchangeably associated therewith and holding means for engaging said element and holding it relatively to said body portion.

10. In a punch of the character described, the combination of a body member and an actuating member cooperatively connected to the body member, said body member being provided with portions which, respectively, carry male and female punching elements, a guide for the male punching element, said 15 guide being provided with means whereby the actuating member may be associated with said male punching element, said body member being provided with a chamber into which punchings may lodge, one wall of the 20 chamber providing a seat for a member which is removably associated therewith, said member providing a means for removably holding the female punching element and means for securing said member to said 25 wall of the chamber.

11. In a punch of the character described, the combination of a body member, and an actuating member cooperatively connected to the body member, said body member being provided with portions which, respectively, carry male and female punching elements, a guide for the male punching element, said 30 guide being provided with means whereby the actuating member may be associated with said male punching element, said guide and male punching element being provided with means which cooperate with each other to 35 maintain the male punching element against rotation, said portion of the body member which carries the female punching element being apertured, and being depressed relatively to the remainder of said body portion, a plate adapted to be removably arranged in the depressed portion, and said plate having a converging aperture, the smaller dimension of the aperture being arranged uppermost, a female die element 40 adapted to be arranged in said aperture and to rest upon the wall of said depression, and means for holding said plate relatively to 45 said body portion.

which carries the female punching element 40 being apertured, a plate having a conical-shaped aperture, the smaller dimension thereof being uppermost and permitting the association of a female cutting die, the side walls thereof corresponding to the inclination of the side walls of the aperture in said plate, and means for holding said plate relatively to said body portion.

12. In a punch of the character described, the combination of a body member, and an actuating member cooperatively connected to the body member, said body member being provided with portions which, respectively, carry male and female punching elements, a guide for the male punching element, said 50 guide being provided with means whereby the actuating member may be associated with said male punching element, said guide and male punching element being provided with means which cooperate with each other to 55 maintain the male punching element against rotation, said portion of the body member which carries the female punching element being apertured, and being depressed relatively to the remainder of said body portion, a plate adapted to be removably arranged in the depressed portion, and said plate having a converging aperture, the smaller dimension of the aperture being arranged uppermost, a female die element 60 adapted to be arranged in said aperture and to rest upon the wall of said depression, and means for holding said plate relatively to 65 said body portion.

In witness whereof, I hereunto subscribe 75 my name this 9th day of March, A. D., 1925.

GEORGE F. McGILL.
